(57) **CLAIM**

The ornamental design for a fishing hook, as shown and described.

DESCRIPTION

FIG. 1 is a perspective view of a fishing hook according to my design;

FIG. 2 is a side view;

FIG. 3 is an opposite side view;

FIG. 4 is a front view;

FIG. 5 is a rear view;

FIG. 6 is a top view; and,

FIG. 7 is a bottom view.

The dashed lines show portions of the fishing hook that form no part of the claimed design.
